UNITED STATES PATENT OFFICE.

ROBERT ASHWORTH, OF ST. CLOUD, MINNESOTA.

HAWSER-CLAMP.

SPECIFICATION forming part of Letters Patent No. 479,777, dated August 2, 1892.

Application filed April 30, 1892. Serial No. 431,237. (No model.)

To all whom it may concern:

Be it known that I, ROBERT ASHWORTH, a citizen of the United States, residing at St. Cloud, in the county of Stearns, State of Minnesota, have invented certain new and useful Improvements in Hawser-Clamps, of which the following is a specification, reference being had therein to the accompanying drawings.

10 My invention relates to devices for uniting one end of a hawser or guy-rope to a portion of the same; and the objects of my improvement are to construct a simple and inexpensive clamp or clip, easily applied and adjusted 15 in position and adapted to grip a guy-rope with increasing force, corresponding with any increasing strain thereon. I attain these objects by the construction illustrated in the accompanying drawings, in which—

20 Figure 1 is a perspective view of a guy-clamp constructed in accordance with my invention and represented as grasping two portions of a rope. Fig. 2 is a longitudinal central section of the same. Fig. 3 is a transverse section on line xx of Fig. 2.

In said drawings, A represents a cap-plate or metal block of substantially rectangular form, through which there is a vertical central perforation a and two perforations a^2 , 30 parallel with the central one and at a short distance therefrom. Said block A has in the bottom thereof two grooves b , made across it, between the perforations a and a^2 and of a width substantially equal to the diameter of 35 the guy-rope C it is intended to clasp. Said block forms one of the members of the clamp. The second member consists of a bolt D, having a T-shaped head, the arms D^2 of which are bent parallel with the body of the bolt D 40 and are of suitable size to enter and be received in the side perforations A^2 of the block A. The body of the bolt is screw-threaded and made to pass through the central perforation a of the block. Upon said screw-threaded body a nut e is placed, the bottom 45

of which rests upon the top of the block A and is adapted to draw the bolt D through the central perforation a , and at the same time the arms D^2 through the perforation a^2 and clamp two portions of the guy-rope between the bottom of the grooves b and the U-shaped loops d^2 , formed in the head of the bolt between its body D and its arms D^2 . To insure the retention of the guy-rope by the two members of the clamp, the grooves b of the block A are concaved at b^2 in the middle of their length, into which cavity a portion of the guy-rope is bent and forced under the pressure of the nut e upon the member D and cannot slip from engagement with the clamp.

To prevent any accidental displacement of the nut e , a jam-nut e^2 is generally placed upon the screw-threaded portion of the bolt D and made to impinge upon the nut e .

Having now fully described my invention, I claim—

1. A guy-clamp consisting of two members and a screw-nut, one member having three parallel perforations and the other member being in the form of a T-headed bolt having its body passing through the central perforation and through the nut and its arms through the other perforations, substantially as described.

2. In a guy-clamp, the combination of a metal block having three perforations parallel with each other and grooves in the bottom thereof between said perforations, a T-headed bolt having its screw-threaded body passing through the central perforation and its arms through the perforations on the sides of the central one, with a nut on said body, substantially as described.

In testimony whereof I affix my signature in presence of two witnesses.

ROBERT ASHWORTH.
